UNITED STATES PATENT OFFICE.

BENJAMIN F. FAUNCE, OF JOHNSTOWN, PENNSYLVANIA.

ADJUSTABLE MILL FOR ROLLING CIRCULAR SECTIONS.

1,341,891.

Specification of Letters Patent.

Patented June 1, 1920.

Application filed July 29, 1919. Serial No. 314,064.

To all whom it may concern:

Be it known that I, BENJAMIN F. FAUNCE, a citizen of the United States, residing at Johnstown, Cambria county, Pennsylvania, have invented certain new and useful Improvements in Adjustable Mills for Rolling Circular Sections, of which the following is a specification.

This invention relates to mills for rolling various circular sections such as steel car wheels, large gears, pulleys etc., and is an improvement in the apparatus disclosed in the Slick Patents Nos. 965,035 and 965,036.

The chief features of novelty reside in the means for adjusting the position of the working face of the normally fixed die in order to compensate for wear thereon and to the particular design and construction of the spacers employed to effect the adjustment of the fixed carriage.

The objects and advantages of my invention will be apparent to those skilled in the art from the following description when read in connection with the accompanying drawings in which:

Figure 1 is a plan view partly in horizontal section;

Fig. 2 is a side elevation thereof;

Fig. 3 is a transverse section on the line 3—3 of Fig. 1;

Fig. 4 is a transverse section on the line 4—4 of Fig. 1;

Fig. 5 is a detail view of my improved form of spacer.

Referring to the drawings 10 represents a supporting structure on which carriages 11 and 12 are guided in the ways 13 and 14 formed thereon. The carriages 11 and 12 form adjustable supports for the complementary forming dies 15 and 16. These dies being carried by holders 17 and 18 having suitable thrust bearings 19 and 20 co-operating therewith to minimize the friction on the bearings thereof during the rolling or forging operation.

The dies are rotated by shafts 21 and 22 from any suitable source of power. In normal operation the carriage 12 is held in a fixed position so that the working face of the die 15 does not move in the direction of its axis. The carriage 11 is provided with suitable means whereby it is moved axially to exert a pressure on the work W supported therein.

In former constructions machines of this type have been so designed and built that

the holder for the fixed die was supported in stationary bearings. With such a construction when it was necessary to adjust the die 15 in axial direction to compensate for the wear thereon, it was necessary to either remove said die and substitute a new one or to insert liners or spacers between it and its holder to correctly position its working face. This was a rather primitive way of adjusting the position of the die and in practice proved to be a slow and inefficient way of making the adjustment.

In the embodiment of my invention herein shown, the die 15 and holder 17 thereof are mounted on the carriage 11 which being slidably supported in the ways 13 permits of an axial movement whereby the wear on the working face of the die may be readily compensated for. Hydraulic cylinders 23 mounted on the supporting structure are adapted to move the carriage 11 in a direction parallel with the axis of the holders 17. An abutment 24 is secured to the supporting structure 10 for limiting the backward movement of the carriage 11 and this abutment carries a pair of outwardly extending bars 25 which support the spacers 26 which are adapted to be interposed between the rear of the carriage 11 and the said abutment 24 in order to vary the position of the working face of the die 15.

These spacers have hooks 27 formed thereon for engagement with the rods 25 and are slotted at 28 to enable their being readily slipped over the shaft 21 which drives the die 15. The spacers 27 as shown clearly in Fig. 1, are of varying thickness and by their use the working face of the die 15 can initially be very accurately adjusted, and as the die wears after use, one or more spacers of different thicknesses may be interposed or substituted for the ones carried by the pins 25 to compensate for the wear on the die 15.

Though I have described with great particularity details of construction of the specific embodiment herein shown, it is not to be construed therefrom that I am limited thereto as changes in construction and substitution of mechanical equivalents may be made by those skilled in the art without departing from the invention as defined in the appended claims.

What I claim is:

1. In a mill for rolling circular sections, carriages having rotatable dies mounted

therein, whose axes extend at an oblique angle to each other, one of said carriages being normally held in a fixed position and the other being mounted so as to permit of movement toward the opposite carriage obliquely to the axis of the die mounted therein, a supporting structure for said carriages and detachable spacers interposed between an abutment on said supporting structure and the fixed carriage, said spacers being adapted to permit substitution of other spacers to compensate for the wear on the die mounted therein.

2. In a mill for rolling circular sections, carriages having rotatable dies mounted therein, one of said carriages being held stationary when in working position and the other being mounted for movement toward said stationary carriage, a supporting structure for said carriages and spacers adapted to be detachably interposed between an abutment on said supporting structure and the fixed carriage to accurately locate the working face of the die mounted therein.

3. In a mill for rolling circular sections, carriages having rotatable dies mounted therein, one of said carriages being normally held in a fixed position, and the other being mounted so as to permit of movement toward the opposite carriage, a supporting structure having an abutment thereon for

said fixed carriage, spacers interposed between said carriage and said abutment to position the working face of the die carried thereby, and means carried by said abutment for supporting said spacers.

4. In a mill for rolling circular sections, carriages having rotatable dies mounted therein, one of said carriages being normally held in a fixed position, means for slidably supporting said carriages, an abutment for one of said carriages, spacers with supporting hooks formed thereon, for adjusting the position of one of said carriages, and rods co-acting with the hooks on said spacers for supporting them.

5. In a mill for rolling circular sections, carriages having rotatable dies mounted therein, one of said carriages being normally held in a fixed position, means for slidably supporting said carriages, an abutment for one of said carriages, spacers with supporting hooks formed thereon, for adjusting the position of one of said carriages, and rods co-acting with the hooks on said spacers for supporting them, said spacers having slots formed therein to permit of their being readily slipped over the shaft supporting the die carried by one of said carriages.

In witness whereof, I have hereunto signed my name.

BENJAMIN F. FAUNCE.
